FRED LA CHAPELLE, OF LYNN, MASSACHUSETTS, ASSIGNEE, BY MESNE ASSIGNMENTS,
TO THOMAS G. PLANT, OF BOSTON, MASSACHUSETTS.

BOBBIN-WINDING MACHINE.

935,263.

Specification of Letters Patent. Patented Sept. 28, 1909.

Application filed December 18, 1907. Serial No. 408,613.

To all whom it may concern:

Be it known that I, FRED LA CHAPELLE, a citizen of the United States, residing at Lynn, in the county of Essex and State of Massachusetts, have invented an Improvement in Bobbin-Winding Machines, of which the following description, in connection with the accompanying drawings, is a specification, like characters on the drawings representing like parts.

The invention to be hereinafter described relates to machines for winding sewing machine bobbins, and more particularly to that type wherein the carrier or bobbin is supplied with a waxed thread to be used in sewing certain portions of boots and shoes, the object of the invention being to provide a simple and efficient device of this character adapted to facilitate the work of the operative and secure economy of equipment.

The invention and its general objects will be best understood from the following description taken in connection with the accompanying drawings illustrative of one form or embodiment thereof.

In said drawings: Figure 1 is a front elevation, parts being in section, of sufficient of a winding machine or apparatus and its adjuncts to make clear the features of the present invention. Fig. 2 is a side elevation thereof looking in the direction of the arrow, Fig. 1. Fig. 3 is a detail showing a face view of the bobbin driving clutch member.

The frame or bracket A is provided with a suitable bearing 1 for the sleeve-shaft 2 having at one end the driving pulley 3, and at its opposite end the collar 4, the construction being such that while the sleeve-shaft 40 is free to rotate in its bearing, it is held from longitudinal movement. The driving pulley 3 may be driven from any suitable source of power, as by a band or the like, and is preferably provided with one member 45 of a clutch device, such as the pin 5.

Extending through the sleeve-shaft 2, is the bobbin driving shaft 6, having secured thereto at one end, as by pin 7, the collar 8, provided with the flange 9 and terminating 50 with a stop-head 10, said stop-head being preferably formed with a flat side-face for a purpose to be presently explained. Disposed within the enlarged bore 11 of the sleeve-shaft 2 and surrounding the bobbin

driving shaft is a coiled spring 12, one end 55 of which rests against the collar 8 and the other against the shoulder 13 at the end of the enlarged bore 11, the effect of such spring being to normally move the bobbin driving shaft to the right, viewing Fig. 1.

Secured to the bobbin driving shaft 6 by suitable means, such, for instance, as the pin 14, is the bobbin driver 15 comprising a barrel 16, terminating at each end in a disk-like element 17 and 18. The part 18, which 65 for identification may be termed the bobbin driving clutch member, is adapted to be received in a face recess of the driving pulley 3, and is provided with a pin receiving socket 19, whereby, upon engagement of the 70 pin 5 with the socket 19, rotation is imparted to the bobbin driving clutch member and disk 17.

Near its outer end the bobbin driving shaft is provided with means for securing 75 the bobbin 20 in driving connection with the bobbin driver, said means, in the present embodiment of the invention, comprising a clamping disk 21 having an interiorly screw threaded sleeve 22, adapted to engage the 80 screw threads 23 on the bobbin driving shaft.

From the construction thus far described it will be apparent to one skilled in the art, that the spring 12, acting on the collar 8, 85 will tend normally to move the bobbin driving clutch member 18 into driving engagement with the driving pulley 3, and hence cause pulley 3 to impart its rotative movement to the bobbin 20 secured between the 90 disks 21 and 17. It will be equally obvious that movement of shaft 6 in the opposite direction will disengage the clutch member 18 from driving connection with the driving pulley 3.

In winding a waxed thread upon a bobbin for use in sewing machine shuttles, it is desirable that the winding be automatically stopped when the bobbin has become filled, and it is equally desirable that the means, by 100 which this action is secured, be not in engagement with the waxed thread during the entire winding operation, as will be understood by those skilled in the art. To this end, as one embodiment of the invention, 105 there is mounted upon the bracket or frame A, a stop shaft 24, Fig. 2, shown as parallel to the bobbin driving shaft 6, said stop shaft

- having an arm 25 provided with a stop finger 26 normally maintained a distance above the axis of the bobbin barrel, when in driving connection with the shaft 6, equal to the 5 half diameter of the wound bobbin. Thus the stop finger 26 will not engage the waxed thread until the windings on the bobbin have been substantially completed. Secured to the stop-shaft near its opposite end is the 10 driving shaft controlling arm 27, Fig. 2, which is relatively so positioned on the stop-shaft with respect to the arm 25 carrying the stop-finger, that when the latter is in its normal position to be engaged by the 15 thread on a filled bobbin, the end of the arm 27 is to one side of the driving shaft axis; and when the stop-finger is moved away from the bobbin the end of the controlling arm 27 will be moved toward the axis of 20 said driving shaft.
- Mounted on the end of the driving shaft controlling arm 27, Fig. 1, is a cam surface 28, which as the arm 27 is raised or moved toward the axis of the driving shaft, engages the rounded end 29 of the stop head 10, and moves the driving shaft endwise against the tension of the spring 12, thereby 25 disengaging the bobbin driving clutch-member 18 from the driving pulley 3.
- When the windings on the bobbin have 30 reached the required diameter, it is desirable that the stopping action of the parts shall be quick and effective to relieve, as far as possible, all injury to the waxed thread by 35 prolonged engagement therewith of the stop finger, and to avoid defective winding, as will be understood by those skilled in the art. Mounted upon the arm 27 is an actuator pin 30 which, when the arm 27 is in its lowest 40 position, defined by a stop 34, and the stop-finger is in its position to engage a filled bobbin, rests against the edge of an actuator, said actuator in the form of invention shown comprising an arm 31, pivotally mounted at 45 32 and having an upper portion provided with an incline 33. A spring 35, acting on the arm 31, tends to move said arm 31 to the right, Fig. 2. From this construction it will be obvious that when the driving shaft controlling arm 27 is in its lowest position resting against the stop 34, the actuator pin 30 will maintain the actuator 31 in the position shown by full lines, Fig. 2; but when the stop finger 26 is met by the thread winding 50 on the bobbin, it will turn the stop-shaft 24 and move the controlling arm 27 to carry the actuator pin 30 above the shoulder 36 on the arm 31, whereupon the arm 31, under the impulse of spring 35, will move quickly 55 to the right into dotted line position causing the incline 33 to move the actuator pin 30 and the arm 27 upward and, consequently, the stop-finger 26 away from the wound bobbin.
- In order that the stop-finger 26 may 60

readily impart to the controlling arm 27 its initial movement to carry the actuator pin 30 above the shoulder 36 of the actuator 31, the surface 37 of the actuator, which is engaged by the pin 30 during the winding operation, 70 is made somewhat inclined or preferably at right angles to the axis of the arm 27 when the parts are in the position shown by full lines, Fig. 2.

Projecting laterally from the end of the 75 controlling arm 27 is a stop-flange 38, which, after the cam surface 28 has moved the driving shaft to disengage the bobbin driving clutch member 18 from the driving pulley 3, comes in contact with a flat face of the stop-head 10, thereby bringing the driving shaft and wound bobbin to rest. Should a flat face of the stop-head 10 be not in parallelism with the surface of the stop flange 38, as the cam 28 moves the driving shaft to disengage the clutch member and pulley, the yielding nature of the actuator 31 will permit sufficient delayed action in the rise of the arm 27 to bring the flange 38 and a flat face on the stop-head into proper engaging 90 position during the rotation of the stop-head without injury to the parts. A pin 42 on the arm 27 contacting with the stop-head prevents the arm 27 moving so far up as to disengage the stop-head from the cam 95 and flange.

As well known by those familiar with sewing machines using waxed thread, it is essential that the thread be maintained at a sufficiently high temperature, whether a shuttle or needle thread, that the requisite pliability be secured for proper action. Heretofore, in winding bobbins with waxed thread for use in such machines, a number of bobbins have been wound and when wanted for 100 use have been properly heated by baking or otherwise, a system both objectionable and expensive, because it requires a large number of bobbins, and when heated after being wound there is lack of uniformity in the 105 diffusion of heat. In the present invention, therefore, the winding devices are preferably supported by a bracket or frame A secured to or forming part of a wax thread sewing machine, so that the attendant operating the sewing machine may wind his 110 own bobbins as needed, and since he uses only one bobbin at a time, only two bobbins are required for any one machine.

The bracket or frame A is preferably 115 made as a hollow casting in part and is heated by steam supplied thereto through a pipe 40 from a suitable source, a pipe 41 being provided to secure drainage or circulation. From the construction described 120 it will be obvious that heat supplied to the bracket or frame A is transmitted to the bobbin and its load, so that, in practice, it is only necessary for the attendant to place an empty 125 bobbin in winding position, depress the stop 130

finger 26 by means of the thumb piece 43, whereupon the clutch member 18 engages the pulley 3; and upon completion of the winding operation the machine is automatically stopped, the bobbin, now filled, being maintained in heated condition on the driving shaft until wanted for use in the shuttle.

It is to be understood that other means than the heated bracket or supporting frame 10 may be employed within the true scope of the present invention to transmit heat primarily to the central portion of the thread mass as it is being wound or after it has been wound, as the invention is generic in 15 this respect, and is not intended to be restricted to the means illustrated which shows only one form or embodiment of the invention.

While details of construction have been 20 described as one of the many forms the invention may assume, it is to be understood that the invention is not circumscribed thereby except in so far as pointed out by the claims which define the essentials thereof.

25 What I claim is:

1. A machine for winding sewing machine bobbins, comprising in combination, 30 bobbin driving means, a stop-finger normally out of contact with the thread wound upon the bobbin, a controlling arm for said bobbin driving means, connections between the stop-finger and controlling arm to impart initial movement to the latter when the desired amount of thread has been 35 wound upon the bobbin, and means including an actuating arm to further move the controlling arm in the same direction to disengage the bobbin driving means.

2. A machine for winding sewing machine bobbins, comprising in combination, 40 bobbin driving means, a stop-finger normally out of contact with the thread wound upon the bobbin, a controlling arm for said bobbin driving means, connections between 45 the stop-finger and controlling arm to impart initial movement to the latter when the desired amount of thread has been wound upon the bobbin, means to further move the controlling arm and disengage the bobbin 50 driving means, and means carried by said controlling arm to stop rotation of the bobbin.

3. In a machine for winding bobbins, the combination of bobbin driving means, a 55 stop-finger normally out of contact with the thread wound upon the bobbin, a controlling arm for said bobbin driving means, connections between the stop-finger and controlling arm to impart movement to said arm 60 when the desired amount of thread has been wound upon the bobbin, a cam movable by said arm to disengage the bobbin driving means, and devices operated by said arm to stop rotation of the bobbin after disengagement 65 of the bobbin driving means.

4. In a machine for winding bobbins, a driving member, a bobbin driving shaft having a bobbin driving clutch member connected thereto, means acting normally to hold said members in driving relation, a 70 stop-shaft, a stop-finger and a controlling arm connected to said stop-shaft, a cam operated by said controlling arm for disengaging said members, and a stop-flange 75 movable by said controlling arm to stop rotation of the bobbin.

5. In a bobbin winding machine, the combination of a bobbin driving shaft, a stop-shaft, a stop-finger and controlling arm connected to said shaft, said stop-finger being 80 normally out of contact with the thread wound upon the bobbin and movable upon completion of the wound bobbin to initially move the controlling arm, an actuator for said controlling arm, means to cause the actuator 85 to complete the movement of the controlling arm after initial movement thereof, and means operated by the controlling arm to stop the machine.

6. In a bobbin winding machine, the combination of a longitudinally movable bobbin driving shaft, clutch members adapted to be engaged and disengaged by longitudinal movement of said shaft, a stop-finger normally out of contact with the thread wound 95 on the bobbin, a controlling arm, connections between the stop-finger and controlling arm to cause the former to impart initial movement to the latter upon completion of a wound bobbin, an actuator having an inclined portion, means for moving the actuator after initial movement of the controlling arm to complete the movement of the said arm, and means under control of said arm for effecting longitudinal movement of 100 the bobbin driving shaft.

7. In a bobbin winding machine, the combination of bobbin driving means comprising clutch members, a stop-finger normally 110 out of engagement with the thread upon the bobbin, a controlling arm connected to said stop-finger, a cam on said controlling arm to cause separation of the clutch members, an actuator for moving the controlling arm to cause said cam to act, and means movable 115 by said controlling arm to stop rotation of the bobbin.

8. In a bobbin winding machine, the combination of bobbin driving means comprising clutch members, a stop-finger 26 normally 120 out of contact with the thread wound on the bobbin, a controlling arm 27, a stop-shaft 24 on which said stop-finger and controlling arm are mounted, a cam 28, and an actuator 31 for said controlling arm.

9. In a bobbin winding machine, the combination of bobbin driving means comprising clutch members, a stop-finger 26, a controlling arm 27, a cam 28 and a stop-flange 38 controlled by said arm, an actuator 31 for 130

said controlling arm, and means for moving the actuator.

10. In a bobbin winding machine, the combination of bobbin driving means comprising 5 clutch members, a bobbin driving shaft movable longitudinally and carrying a stop-head, a stop-finger and controlling arm operatively connected, a cam actuated by said controlling arm to contact with the stop-head and move the bobbin driving shaft longitudinally, and means also actuated by the controlling arm for contacting with the stop-head to stop rotation of the bobbin.

11. In a winding machine for winding 15 waxed thread upon a bobbin, a bracket or frame having a bearing therein, bobbin winding means supported by said bearing, means for heating said bearing and the bobbin winding means during the winding 20 operation to secure a uniform temperature throughout the wound mass, and means, comprising a stop finger normally out of contact with the thread wound upon the bobbin, to stop the winding operation when 25 the bobbin has become filled.

12. In a machine for winding sewing machine bobbins, the combination of bobbin driving means, a stop-shaft, a controlling arm secured to said shaft, means under control 30 of said arm for stopping the winding operation, an actuator for said controlling arm, means for locking the actuator and controlling arm in bobbin winding position, a stop-finger for giving initial movement to 35 the controlling arm and tripping the locking means when the bobbin has been wound, and means to then move the actuator and through it continue the movement of the controlling arm in the same direction to stop 40 the winding operation.

13. In a winding machine for winding waxed thread, the combination of a bracket or frame, winding means supported by said bracket or frame, means for heating said 45 bracket or frame and for transmitting heat from said bracket or frame to the interior of the thread mass produced by said winding mechanism.

14. In a winding machine for winding 50 waxed thread, the combination of a bracket or frame, having a bearing therein, a bobbin winding shaft supported in said bearing, means for heating the bobbin winding shaft and transmitting heat to the interior of the 55 mass of waxed thread wound upon the bobbin, a stop finger normally out of contact with the thread wound upon the bobbin, and means actuated by said stop finger to stop

the winding operation when the bobbin has been fully wound.

15. In a machine for winding bobbins, the combination of bobbin driving means, a stop-finger normally out of contact with the thread wound upon the bobbin, a controlling arm for said bobbin driving means, connections between the stop-finger and controlling arm to impart movement to said arm when the desired amount of thread has been wound upon the bobbin, a cam movable by said arm to disengage the bobbin driving means, devices operated by said arm to stop rotation of the bobbin after disengagement of the bobbin driving means, and means to transmit heat to the interior of the bobbin through the bobbin driving means.

16. In a winding machine for winding thread, the combination of means upon which the thread is wound, driving means for said winding machine, and means for transmitting heat primarily through the means upon which the thread is wound to the center of the thread mass.

17. In a winding machine for winding thread, the combination of driving means for said winding machine, a stop finger normally out of contact with the thread as it is wound and movable into and out of normal position for contacting with the wound thread when the desired amount has been wound, and means operative by movement 90 of the stop finger toward the center of winding to start the driving means and operative by movement of the stop finger in the opposite direction to stop the driving means.

18. In a winding machine for winding 95 thread or the like, the combination of means upon which the thread is wound, driving means for winding the thread on said first mentioned means, and means for transmitting heat primarily to the center of the 100 thread mass.

19. In a machine for winding thread, the combination of a supporting frame, means on which the thread is wound, driving means for said winding machine, and a heat conduit for transmitting heat primarily through the means upon which the thread is wound to the center of the thread mass.

In testimony whereof, I have signed my name to this specification, in the presence of 110 two subscribing witnesses.

FRED LA CHAPELLE.
